UNITED STATES PATENT OFFICE.

HILMAR E. BINKELE, OF LOS ANGELES, CALIFORNIA.

APPARATUS FOR FACILITATING WINDOW CLEANING.

Application filed April 22, 1924. Serial No. 708,152.

To all whom it may concern:

Be it known that I, HILMAR E. BINKELE, a citizen of the United States, and a resident of Los Angeles, in the county of Los Angeles and State of California, have invented certain new and useful Improvements in Apparatus for Facilitating Window Cleaning, of which the following is a specification.

My invention relates to windows of the sliding sash type, and a purpose of my invention is the provision of an apparatus which can be readily applied to a window irrespective of its dimensions in such manner that the sashes thereof can be swung inwardly from the window frame and supported in position to permit cleaning of both sides of either sash from a point interiorly of a building, thereby eliminating the present practice of cleaning windows exteriorly of the building, and the dangers attendant such practice.

I will describe only one form of apparatus for facilitating the cleaning of windows embodying my invention, and will then point out the novel features thereof in claims.

In the accompanying drawings—

Figure 1 is a view showing in front elevation one form of apparatus embodying my invention in applied position with respect to a window;

Figure 2 is a vertical sectional view taken on the line 2—2 of Figure 1;

Figure 3 is a fragmentary view similar to Figure 2, and showing one of the window sashes swung to cleaning position and a gripping member of one sash clamped in engagement with the corresponding sash;

Figure 4 is a horizontal sectional view taken on the line 4—4 of Figure 1;

Figure 5 is a view similar to Figure 4, showing the window sashes removed from the frame and in cleaning position;

Figure 6 is a vertical sectional view taken on the line 6—6 of Figure 2;

Figure 7 is a horizontal section taken on the line 7—7 of Figure 6;

Figure 8 is a view similar to Figure 7, showing a modification of the sash supporting member shown in Figure 6.

Similar reference characters refer to similar parts in each of the several views.

Referring specifically to the drawings, my invention in its present embodiment is shown applied to a window having a frame 15 of conventional form and including a sill 16 provided with a groove 17 lined with a metal

strip 18. The purpose of the groove and strip will be described hereinafter. The confronting side portions of the window frame 15 are provided with the usual stationary stop beads 19 and also with removable stop beads 20 and 21, the latter co-operating with the stationary beads to provide the channels in which the lower and upper sashes S and S' are adapted to slide. The stop beads consist of a strip removably fitted within a suitable groove formed in the window frame, while the bead 21 is of T-form in cross section, as clearly shown in Figure 4, and is removably fitted in a similar groove formed in the window frame.

The apparatus embodying my invention comprises a bracket designated generally at B, which is adapted to be securely clamped to the window sill 16 through the medium of a clamp, designated generally at C. The bracket B supports in upright position a standard designated generally at T, upon which sash clamps are vertically adjustable to engage or disengage the sashes S and S'. These sash clamps are hingedly connected to the standard so that when in clamping position with respect to the sashes they can be swung from the position shown in Figure 4 inwardly to the position shown in Figure 5, and which latter position I term a cleaning position.

The bracket B includes a substantially L-shaped member 22 having a plate 23 cast integral with the base portion thereof, which is formed with a depending lip 24 adapted to engage the inner edge of the sill 16 and project into the groove 17, all as clearly shown in Figure 2. This plate 23 constitutes a part of the clamp C, the latter also including a curved arm 25 having its upper end formed with a head 26 which is slotted to slidably receive a screw bolt 27 removably secured in the plate 23 and provided with a wing nut 28, by means of which the bolt can be drawn into tight engagement with the head so as to secure the plate 23 in any horizontally adjusted position upon the arm 25. The lower end of the arm 25 is provided with a padded foot 29 which is adapted to bear against the inner side of the sill, as shown in Figure 2. It will be understood that by first positioning the arm 25 and then adjusting the plate 23 to cause the lip 24 to engage the inner edge of the sill 16, the bracket B can be securely positioned upon the sill.

105

110

The member 22, as shown in Figure 2, is provided with vertically aligned sleeves 30 and 31 of angular form in cross section and receiving a tube 32 of similar shape in cross section. This tube constitutes a part of the standard T and the latter also includes a rod 33 angular in cross section and adjustable vertically within the tube 32, a set screw 34 being provided for securing the rod in any vertically adjusted position. A second tube 35 is supported upon the rod 33 and is designed for the purpose of providing supporting means for the gripping members of the sash clamps, as will be more fully described hereinafter. The upper end of the rod 33 is provided with a right angularly disposed arm 36 having a head 37 which is adapted to seat within a socket 38 secured to the upper side of the window frame 15.

By loosening the set screw 34 the rod 33 can be adjusted to move the head 37 into or out of the socket 38, and to provide manual means for moving the rod a manipulating rod 39 (Figure 1) is mounted for vertical movement in a guide 40 formed on the bracket B. This rod 39 is provided with a handle 41, and at its upper end is adapted to be connected to an L-shaped extension 42 which has threaded engagement with the rod 33 so that when the rod 39 is moved vertically through the medium of the handle 41 a corresponding movement of the rod 33 is effected.

Two sash clamps are provided, one for each of the sashes S and S', and the sash clamp for the lower sash S comprises a supporting member 43, which receives the lower rail of the sash S and a gripping member 44 which receives the meeting rail of the sash S. The member 43 is connected by means of a double hinge 45 to the tube 32, the latter being formed with an integral extension 46 to which the hinge 45 is connected. The gripping member 44 is connected to a bracket 47 through a double hinge 48, and the bracket is adjustable vertically upon the tube 35 and adapted to be locked in any adjusted position by means of a set screw 49. As clearly shown in Figure 1, the members 43 and 44 are shaped to receive the lower and upper edge, respectively, of the lower and meeting rails of the lower sash S, and pins 50 are formed on the members for engagement within sockets formed in the sash rails to prevent horizontal movement of the members upon the rails after they have been once applied. From this description it will be seen that the clamp for the sash S includes a stationary supporting member and a gripping member which is adjustable to allow the positioning of the sash upon the supporting member and the subsequent gripping of the sash between the two members when the gripping member is moved downwardly to engage the meeting rail of the sash. After the application of the gripping member it is to be understood that the set screw 49 is adjusted to lock the bracket 47 on the tube 35 so that the sash as a unit is firmly clamped between the members 33 and 34.

The clamp for the upper sash S', also includes a relatively stationary supporting member 51 provided with a rod 52 of angular cross section slidably fitted in a sleeve 56 extending through the socket 54 and engaging the rod 52. The casting 55, together with the member 51, is supported for movement on the socket 31 by a double hinge section 55^a connected to an extension 55^b of the bearing 31. In the present instance I have shown the upper sash S' provided with depending ornamental extensions 57, and in order to adapt the casting 55 to a sash of this construction such sash is provided with a socket 58 for receiving the extension 57, as clearly shown in Figure 6. When employing the casting in connection with a sash not provided with the extensions 57, I employ the construction disclosed in Figure 8, wherein the supporting member 59 corresponding to the member 51 in Figure 6 is elongated and provided with a depending rod 60 adjacent one end and movable within a sleeve 61 and adapted to be locked in any vertical position by means of a set screw 62. The opposite end of the member 59 is provided with a depending extension 63 to fit within the socket 58, and to thus take the place of the ornamental extension 57 in Figure 6. The gripping member, designated at 64, of the sash clamp is constructed in the same manner as the gripping member 44 and is likewise provided with a peg 65 engaging within a socket 66 of the upper rail of the sash. This gripping member, as shown in Figure 2, is connected to an arm 67 of a bracket 68 through a double hinge 69, and the bracket 68 is adjustable vertically upon the tubes 35 through the medium of set screws 70. By positioning the upper sash S' upon the supporting member 51, as shown in Figure 6, and then moving the gripping member 64 downwardly to engage the upper rail of the sash, the sash as a unit is firmly gripped by the clamp for subsequent movement.

The operation of the apparatus is as follows:

With the bracket B, clamp C and standard T in applied position with respect to a window frame, as shown in Figures 1 and 2, the gripping member 44 is first moved to a clamping position with respect to the lower sash S when, by removing the stop

bead 21, the sash as a unit can be swung inwardly from the window frame to the right angular position shown in Figure 5. In this position of the sash both sides of the window pane are readily accessible for cleaning purposes. After the cleaning of this pane has been effected, the upper sash S' can likewise be moved inwardly by first applying the gripping member 64 to the sash, it being understood that the supporting member 51 has been previously applied, and then removing the bead 20, whereupon the upper sash can then be swung inwardly to the right angular position shown in Figure 5, or to any intermediate position so that both sides of the window pane are accessible for cleaning. The double hinge connections between the clamps and the brackets allow of the movement of the sashes from their normal position inwardly to the right angular position, and in such manner that the movement of one sash and its supporting means does not interfere with that of the other. In order to prevent binding of the window sashes during their initial inward movement, the vertical rails of the sashes are slightly beveled as indicated at 71 (Figure 4).

Subsequent to the cleaning of the window pane the sashes can be returned to normal position within the window frame, the bead 20 being replaced after the upper sash is in position, and the bead 21 after the lower sash is in position. By upward adjustment of the members 44 and 64 such adjustment being effected through a loosening of the screws 49 and 70, the members can be moved free of the sashes so that by slightly raising the latter they will be disengaged from the supporting members 43 and 51. The entire apparatus can now be removed from the window by first disengaging the head 37 from the socket 38 and releasing the clamp C from the sill 16.

Although I have herein shown and described only one form of apparatus for facilitating the cleaning of windows, it is to be understood that various changes and modifications may be made herein without departing from the spirit of the invention and the spirit and scope of the appended claims.

What I claim is:

1. In an apparatus of the character described, a standard, brackets on the standard, sash clamps carried by the brackets, each of said clamps including a lower supporting member and an upper gripping member, both of said members being flanged and provided with pins, and hinge connections between the members and their respective brackets.

2. An apparatus of the character described comprising a bracket, an adjustable clamp for securing the bracket, to the sill of

a window frame, an extensible standard supported in the bracket, sash clamps including supporting members having hinge connections with one portion of the stand-

ard, and gripping members, brackets adjust- 70
able on the other portion of the standard and having hinge connections with said gripping members.

3. An apparatus of the character described comprising a bracket, an adjustable clamp 75
for securing the bracket to the sill of a window frame, means for preventing marring of the sill by said clamp, a standard including a stationary portion mounted in the bracket and a movable portion supported in the stationary portion and adjustable thereon, an offset extension on the movable portion provided with a head adapted to engage within a stationary socket secured to the window frame, manually operable means for moving the movable portion to cause said head to engage or disengage within said socket, and sash clamps supported by the standard and including gripping members 80
adjustable thereon. 85

4. An apparatus of the character described comprising a bracket, and adjustable clamp 90
for securing the bracket to the sill of a window frame, means for preventing marring of the sill by said clamp, a standard including a stationary portion mounted in the bracket and a movable portion supported in the stationary portion and adjustable thereon, an offset extension on the movable portion provided with a head adapted to engage within a stationary socket secured to the window frame, manually operable means for moving the movable portion to cause said head to engage or disengage within said socket, sash clamps including supporting members having double hinge connections with the stationary portion of the standard, and gripping members adjustable on and having double hinge connections with the movable portion of said standard. 95

5. In an apparatus of the character described, a sash clamp including a member, a supporting member adjustable on the member, and a pocket in the member adapted to receive an extension of a window sash. 100

6. In an apparatus of the character described, a sash clamp including a body supported for pivotal movement in a horizontal plane, a supporting member adjustable on the body, said body being formed with a 105
pocket for the purpose described.

7. In an apparatus of the character described, a sash clamp including a body supported for pivotal movement in a horizontal plane, and having sockets therein adapted to receive members for adjustably supporting supporting members. 115

8. An apparatus of the character described comprising an extensible standard having a fixed portion and an adjustable portion, a 120
125

member movable on the adjustable portion, brackets movable on the member and having means for securing the brackets to the member and the member to the adjustable portion, and gripping members pivotally supported on the brackets.

9. An apparatus of the character described comprising a bracket, means for securing the bracket to the sill of a window frame, a 10 standard including a stationary portion mounted in the bracket, and a movable portion supported by and adjustable on the stationary portion, a member adapted to be secured to a window frame, manually operable means for moving the movable portion to engage or disengage the member, and sash clamps supported by the standard and including gripping means adjustable thereon.

10. An apparatus of the character de-

scribed as embodied in claim 9 wherein said bracket is provided with a depending flange adapted to engage within a socket formed in the sill of the window frame.

11. An apparatus of the character described comprising a bracket, an adjustable clamp for securing the bracket to the sill of a window frame, a standard including a stationary portion mounted in the bracket and a movable portion supported in the stationary portion and adjustable thereon, means for detachably securing said movable portion to the window frame, sash clamps including supporting members having hinge connections with the stationary portion of the standard, and gripping members adjustable on and having hinge connections with the movable portion of said standard.

HILMAR E. BINKELE
